MEANS FOR CONNECTING INTERNAL COMBUSTION ENGINES TO SUCTION MOTORS

Fred H. Stroup, Kirkwood, Mo., assignor to Wagner Electric Corporation, St. Louis, Mo., a corporation of Delaware

Application April 26, 1937, Serial No. 138,890

6 Claims. (Cl. 60—60)

My invention relates to suction-operated mechanism and more particularly to means for connecting said mechanism to the intake manifold of an internal combustion engine.

5 One of the objects of my invention is to provide improved means for connecting a suction motor to the intake manifold of an internal combustion engine whereby the operation of the suction motor will not adversely affect the operation 10 of the engine during the introduction of air into the manifold.

Another object of my invention is to associate 15 an expansion chamber with the portion of the intake manifold which is connected to a suction-operated motor to thereby cause a decrease in the density of the air prior to its passage into the intake manifold and its mixing with the carbureted mixture.

Still another object of my invention is to associate 20 with the intake manifold of an internal combustion engine, means for more evenly distributing the air introduced into the manifold from the suction motor.

Other objects of my invention will become apparent 25 from the following description taken in connection with the accompanying drawing in which Figure 1 is a side view of a portion of the intake manifold and carburetor having associated therewith an embodiment of my invention; Figure 2 is a cross-sectional view taken on the line 2—2 of Figure 1, showing the inlet spacer; 30 Figure 3 is a cross-sectional view of the spacer taken on the line 3—3 of Figure 2; and Figure 4 is a view similar to that of Figure 1, showing a modified construction.

Referring to Figures 1, 2, and 3, the reference character 1 indicates a portion of an internal combustion engine and 2 the intake manifold for said engine which has an inlet pipe 3 for association with the carburetor 4. Between the inlet pipe and the carburetor is interposed a spacer member 5 suitably secured to flanges on the carburetor and the inlet pipe by means of bolts 6. This spacer member is provided with two passages 7 and 8 which are aligned with similar passages of the carburetor and of the inlet pipe. The wall of the spacer member is also provided with a chamber 9 which completely surrounds passages 7 and 8 and this chamber communicates with passage 7 by means of spaced restricted openings 10 and with passage 8 by means of spaced restricted openings 11. One side of this chamber, at a point substantially opposite the partition between passages 7 and 8, is connected by means of a conduit 12 to the suction

motor 13, the conduit being provided with a valve 14 for controlling communication between the motor and chamber 9. The suction motor and valve are only diagrammatically shown and may be any one of a number of types, as for example, a control valve and power cylinder for operating a clutch or a brake mechanism, or a reversing valve and motor for operating a compressor for compressing air for use as a source of power to operate different mechanisms which are found on an automobile or other structure. A portion of the chamber opposite that to which conduit 12 is connected is in communication with the expansion chamber 15 by means of a passage-way 16, this expansion chamber being screwed 15 into a suitable boss 17 on the spaced member. The chamber 15 may be of different sizes, depending upon the type and size of the suction motor associated with the manifold, its capacity, however, being in excess of that of chamber 9 20 which surrounds and communicates with passages 7 and 8.

In the operation of the mechanism just described, when the suction motor is inoperative, expansion chamber 15 will have the same degree 25 of vacuum as that of the intake manifold during all conditions of operation of the engine since this chamber is in constant communication with passages 7 and 8 by means of openings 10 and 11. If the suction motor is now operated by 30 proper control of valve 14, the air in the suction motor will be immediately drawn into chamber 9 because of its vacuum condition. This air, instead of being drawn directly into passages 7 and 8 through which the carbureted mixture flows to the cylinders of the engine as would be the case if conduit 12 were connected directly to the passages, is discharged into chamber 9. Since the expansion chamber 15 is directly connected to chamber 9, the degree of vacuum therein decreases and a portion of the air which enters chamber 9 from the suction motor will also enter the expansion chamber. The air under atmospheric pressure coming from the suction motor will, therefore, become rarefied, that is, decreased 35 in density and reduced in pressure prior to its entry into passages 7 and 8 through openings 10 and 11. This rarefied air will enter passages 7 and 8 at different points about their walls due to the spacing of openings 10 and 11 and thus 40 will mix with the carbureted mixture flowing to the cylinders of the internal combustion engine. The operation of the engine will thus not be seriously affected by any excess unmixed air 45 50 55

being introduced into one or more of the engine cylinders.

When the suction motor is employed to actuate the compressing piston of an air compressor, 5 the motor will be subject to intermittent operation, and the expansion chamber 15, besides causing a rarefaction of the air coming from the suction motor, will also "smooth out" or "dampen" the pulsations caused by the intermittent flow of 10 air from the suction motor to the manifold. In other words, if the expansion chamber were not present and conduit 12 directly connected to inlet pipe 3 of the manifold, the intermittent charges of air resulting from the operation of the 15 suction motor during the compressor operation will cause the carbureted mixture to vary in density each time air is introduced into the inlet pipe and, as a result, there would be uneven operation of the engine ordinarily termed "rolling". This 20 "rolling" would be in timed relation with the operation of the suction motor. By the use of the expansion chamber 15, chamber 9, and spaced openings communicating with passages 7 and 8, the intermittent flow of air from the suction motor 25 during its operation is caused to have a fairly even flow into the inlet pipe as expansion chamber 15 and chamber 9 decrease the density of the air, and passages 10 and 11 tend to introduce this rarefied air into passages 7 and 8 at 30 a uniform rate.

It is not necessary for expansion chamber 15 to be placed upon the side of the spacer opposite that to which conduit 12 is connected. In Figure 4 I have shown the expansion chamber 15' as 35 being interposed between conduit 12' and chamber 9 of the spacer member. When the suction motor is inoperative, this expansion chamber has the same degree of vacuum as the inlet pipe of the manifold. When the suction motor is operated, the air therefrom is first introduced into expansion chamber 15' and chamber 9 where its 40 density is decreased prior to being evenly distributed into passages 7 and 8 through openings 10 and 11. Thus chamber 15', in this position, 45 acts in the same manner as does chamber 15 of the structure shown in Figure 1, and the operation of the engine is not affected while the suction motor is being operated.

Being aware of the possibility of modifications 50 in the particular structure herein described without departing from the fundamental principles of my invention, I do not intend that its scope be limited except as set forth by the appended claims.

Having fully described my invention, what I 55 claim as new and desire to secure by Letters Patent of the United States is:

1. In apparatus of the class described, the combination of an intake manifold passage of an 60 internal combustion engine, means forming a chamber surrounding said passage, said chamber communicating with said passage by means of restricted openings through the wall thereof, a suction motor, a conduit for placing the motor 65 in communication with the chamber, and an expansion chamber in constant communication with the chamber surrounding the manifold passage.

2. In apparatus of the class described, the combination of an intake manifold passage of an internal combustion engine, means forming a chamber surrounding said passage, said chamber communicating with said passage by means 5 of restricted openings through the wall thereof, a suction motor, a conduit for placing the motor in communication with the chamber, and an expansion chamber in constant communication with the chamber surrounding the manifold passage, said expansion chamber having a volumetric capacity exceeding that of the first mentioned chamber. 10

3. In apparatus of the class described, the combination of an intake manifold passage of an internal combustion engine, means forming a chamber surrounding said passage, said chamber communicating with said passage by means 15 of a restricted opening through the wall thereof, an expansion chamber in constant communication with one side of said chamber surrounding the manifold passage and having a volumetric capacity exceeding that of said chamber surrounding the passage, a suction motor, and a conduit for placing said motor in communication 20 with the chamber surrounding the passage and on the side opposite that with which the expansion chamber communicates. 25

4. In apparatus of the class described, the combination of an intake manifold passage of an internal combustion engine, means forming a chamber surrounding said passage, said chamber communicating with said passage by means 30 of a restricted opening through the wall thereof, an expansion chamber in constant communication with said chamber surrounding the manifold passage and having a volumetric capacity exceeding that of said chamber surrounding the passage, a suction motor, and a conduit connecting the motor with the expansion chamber. 35

5. In apparatus of the class described, the combination of an intake manifold of an internal combustion engine, a carburetor, a member interposed between the carburetor and the intake manifold and having an opening in alignment 40 with the outlet of the carburetor and the inlet of the manifold, means forming a chamber in the wall of said member and surrounding the opening, said wall being provided with spaced restricted connecting passages for placing the 45 opening in communication with the chamber, an expansion chamber having a volume considerably greater than the chamber in the wall of the member and communicating with said wall chamber, a suction-operated motor, and means for placing said motor in communication with the wall chamber. 50

6. In apparatus of the class described, the combination of a fuel intake passage of an internal combustion engine, a suction-operated motor, 60 conduit means including a restricted opening in the wall of the intake passage for connecting the suction motor with the passage, and means forming an expansion chamber in constant communication with said intake passage through said restricted opening. 65
